US00D830765S

(12) **United States Design Patent** (10) **Patent No.:** **US D830,765 S**
(45) **Date of Patent:** **** Oct. 16, 2018**

(54) **LID FOR CONTAINER**

(71) Applicant: **RUBBERMAID INCORPORATED**,
Huntersville, NC (US)

(72) Inventors: **William F. Croft**, Mooresville, NC
(US); **Evan Allen Fulford**, Portage, MI
(US); **William Hart**, Cornelius, NC
(US); **Gianna Lint**, Cornelius, NC (US)

(73) Assignee: **Rubbermaid Incorporated**,
Huntersville, NC (US)

(**) Term: **15 Years**

(21) Appl. No.: **29/557,031**

(22) Filed: **Mar. 4, 2016**

(51) LOC (11) Cl. **07-99**

(52) U.S. Cl. **D7/391**

(57) **CLAIM**

The ornamental design for a lid for container, as shown and described.

DESCRIPTION

FIG. 1 is a top perspective view of a lid for container;
FIG. 2 is a front view of a lid for container illustrated in FIG. 1;

FIG. 3 is a rear view of a lid for container illustrated in FIG. 1;

FIG. 4 is a right side view of a lid for container illustrated in FIG. 1;

FIG. 5 is a left side view of a lid for container illustrated in FIG. 1;

FIG. 6 is a top view of a lid for container illustrated in FIG. 1; and,

FIG. 7 is a bottom view of a lid for container illustrated in FIG. 1.

The broken lines are shown for the purpose of illustrating parts of the article that form no part of the claim.

1 Claim, 5 Drawing Sheets
